CENTERING DEVICE FOR PLASTIC FUNNELS

Filed March 10, 1947

FIG. 1

UNITED STATES PATENT OFFICE

2,577,866

CENTERING DEVICE FOR PLASTIC FUNNELS

Wesley L. Webb, Glenmoore, Pa., assignor to
American Viscose Corporation, Wilmington,
Del., a corporation of Delaware

Application March 10, 1947, Serial No. 733,585

10 Claims. (Cl. 33—46)

1
This invention relates to the spinning of artificial filaments, strands, cords, threads or the like. More particularly this invention relates to a device employed to center spinning funnels in spinning buckets or the like.

It is of great importance that spinning funnels are centered in spinning buckets. These spinning funnels reciprocate longitudinally in the rotating spinning bucket. As the funnel reciprocates, thread or the like is fed through it and due to the centrifugal force created by the rapidly rotating spinning bucket, it is thrown to the outer periphery of the spinning bucket and evenly wound into a cake. However if the funnel is not properly centered, the threads or the like will not be wound symmetrically and will become tangled making it almost impossible to unwind formed cakes.

Each spinning bucket has a colored circular mark imprinted in the center of its base. This circular mark is of substantially the same diameter as the spinning funnel at the point where the thread emerges. Heretofore a flashlight was directed through the funnel to determine the relationship between the beam of light and the imprinted circular mark. If it was properly centered the beam of light would be coincident with the circular mark or concentric with the circular mark if the circular mark was of a greater diameter than the beam of light. However using a flashlight was makeshift at best and a greater percentage of the time the spinning funnel was improperly centered. This was due to the diffusion of the flashlight's rays and also due to the fact that it was difficult to center the funnel when it had to be adjusted while holding the flashlight which made this method slow and tedious. These disadvantages of centering are overcome in the present invention.

The primary object of the present invention is to provide an improved device for accurately centering a spinning funnel in a spinning bucket or the like.

Other objects and advantages of the present invention will become apparent from a study of the following drawings and descriptions herein-after.

In the drawings

Figure 1 is a top view of a preferred embodiment of the present invention.

Figure 2 is a side elevation of Figure 1.

Figure 3 is a side elevation partly in section of a preferred embodiment of the present invention taken along line III—III of Figure 1 but with a spinning funnel in position.

2
As shown in Figures 2 and 3, reference character 1 represents the housing of the present invention. Extending from the lower portion of the housing 1 is an annular projection 2 into which an annular adapter member 3 is seated. This adapter 3 is readily interchangeable with other adapters having the same outside diameter but a different inside diameter. The variable inside diameters of the adapters compensate for funnels of different diameters. The housing 1 is supported in place by the flared end 4a of the funnel 4 which fits snugly inside the adapter 3 and against the lower annular seat 1a at the lower end of the housing inside the adapter and prevents any wobbling or tilting of the housing. Said funnel 4 is supported by a funnel bracket arm 43.

Directly over the funnel on a common centerline and supported in the housing 1 is a microscope lamp lens system 5 consisting of two or more lens elements. Although it is not shown the lens system may include a diaphragm to vary the size of the beam of light projecting through the funnel. This lens assembly 5 may or may not project into the annular projection 2. However as shown in this embodiment it extends from a point part way below the housing 1, through the more or less central bore 5a in the housing to a point a suitable distance below the light source 6. The lamp 6 is held in its socket 7 which is suitably secured inside the cover member 8. As shown in Figure 1 the cover member 8 is secured to the housing 1 by four screws 9, 10, 11 and 12. However it is to be understood that this cover may be attached in any other way such as by clamps, studs or the like.

The screws 9, 10, 11 and 12 also center the light source 6 relative to the bore so that it is on the centerline common to the microscope lens system 5 and the funnel 4. With the microscope lens system 5 so placed it parallelizes the rays from the light source 6 and projects them through the funnel 4 with a minimum of diffusion and concentrates them at a point 41 on the base 42 of the spinning bucket.

Placed on opposite sides of the microscope lens system 5 in the housing are two dry cells 13 and 14. The dry cell 13 is contained in a cylindrical recess 15 that is countersunk at its base to form a smaller cylindrical recess 17 into which is placed a spring 18. Similarly the dry cell 14 is contained in a cylindrical recess 16 which is countersunk to form another cylindrical recess 19 into which a toggle switch 20 is secured. The portion of 55 the cover 8 over the dry cell 14 is also counter-

sunk to form a cylindrical recess 18 into which the spring 22 fits.

The springs 18 and 22 have a two-fold purpose. One is to act as an electrical conductor to the negative electrodes of the dry cells and the other is to press against the dry cells so that the positive electrodes contact the conductors 23 and 24. The conductor 23 as shown is a screw. However it is to be understood that this can be of any shape or design as long as it is a conducting material. The conductor 24 is secured in a washer 25 or the like which is held in place by the annular ledge 26 which was created by the formation of the small cylindrical recess 18 in the base of the cylindrical recess 16. The conductor 24 is connected at one end to the positive electrode of the dry cell 14 and at its opposite end to a wire conductor 27 which is in turn connected to the one side of the toggle switch 28. The other side of the toggle switch is connected to the spring 18 by a wire conductor 28 which passes through the groove 26 which is filled with black filler, wax or the like as shown in Figure 3. The current then passes through the dry cell 14 from its positive electrode to the conductor 23. The conductor 23 is connected to another conductor 31 by a wire 30. The conductor 31 makes contact with the lamp at 32. The other side of the lamp at 34 is connected by a wire 36 to the conductor 38 which contacts the spring 22. As shown by reference character 33 the top of the cover member 8 is grooved to accommodate the wires 30 and 36. This groove is also filled with black filler, wax or the like when the wires are in place as shown in Figure 1. As can be seen from the foregoing disclosure a complete series circuit is formed. All that is necessary to operate the lamp is to turn the toggle switch 28 to "on" or "off."

A further unique feature of the present invention is the attached bulb type pressure pump 37 which is connected to the sleeve member 38 on the hollow passage 39. A hollow passage 40 connects the hollow passage 39 with the atmosphere at the top of the funnel 4, said atmosphere being substantially enclosed by engagement of the rim of the funnel with the seating surface 1a of the housing 1 to produce a surge through the funnel and the stem thereof, of air or other gas forced into the atmosphere of the funnel through the passages by the pump 37.

When the operator wishes to center a funnel he places the annular projection 2 over the funnel 4 with the seating surface 1a in engagement with the top edges of the funnel and turns the lamp on. He then squeezes the pressure bulb 37 to blow out the drop of acid collecting in the funnel tip. This action allows the beam of light to pass through. With the device thus positioned on the funnel and a sharp beam of light passing through it the operator can use both hands to accurately position the funnel. In positioning the funnel 4 the lock nuts 44 and 45, which are screwed on the threaded sleeve 46, fixedly secured on said funnel are loosened. Since the funnel bracket support 43 has a bore 47 which is larger in diameter than the sleeve member 46 the funnel is free to move to any position in the horizontal plane. Movement of the funnel in the vertical direction is accomplished by loosening either locking nut and tightening the other.

Although this invention has been described with reference to improvements shown, it will readily be appreciated that numerous changes may be made without departing from the spirit and scope

of the invention as described in the appended claims.

I claim:

1. An apparatus for centering a spinning funnel comprising a housing, a surface for seating said housing on the funnel, a lamp within the housing, means within the housing for concentrating light from the lamp into a beam of small cross-section having substantially parallel rays, means for positioning the device on the funnel with the beam centered with respect to, and aligned to shine through, the funnel, and means for expelling liquid from the lower end portion of the funnel.
2. An apparatus for centering a spinning funnel comprising a housing, a surface for seating the housing on the funnel, a lamp within the housing, means within the housing for concentrating light from the lamp into a beam of small cross-section having substantially parallelized rays, electrical means within the housing for lighting the lamp, means for positioning the device on the funnel with the beam centered with respect to, and aligned to shine through, the funnel, and means for expelling liquid from the lower end-portion of the funnel.
3. An apparatus for centering a spinning funnel comprising a housing, a surface for seating the housing on the funnel, a lamp within the housing, means between the lamp and the surface for concentrating light from the lamp into a beam of small cross-section having substantially parallelized rays, means for positioning the device on the funnel with the beam centered with respect to, and aligned to shine through, the funnel, and pneumatic means in communication with the interior of the housing for expelling liquid from the lower end-portion of the funnel.
4. An apparatus for centering a spinning funnel in a spinning bucket comprising a housing, a cover secured to said housing, a surface for seating said housing on the funnel, a lamp in the cover, electrical means in the housing for lighting the lamp, means in the housing between the lamp and the funnel for directing light from the lamp through the funnel, means for expelling liquid that collects at the tip of the funnel, and conduit means through the housing connecting the means for expelling the fluid and a portion of the seating surface facing into the top of the funnel.
5. An apparatus for centering a spinning funnel in a spinning bucket comprising a housing, a surface for seating said housing on the funnel, a cover secured to said housing, a projection extending from the housing into which the funnel extends when said housing is seated over the funnel, a lamp in the cover, electrical means in the housing for lighting the lamp, means in the housing between the lamp and the funnel for directing light from the lamp through the funnel, means for expelling liquid that collects at the tip of the funnel, and conduit means connecting the means for expelling the fluid and a portion of the seating surface facing into the top of the funnel.
6. An apparatus for centering a spinning funnel in a spinning bucket comprising a housing, a surface for seating said housing on the funnel, a cover secured to said housing, an annular projection extending from the housing into which the funnel extends when said housing is seated over the funnel, a lamp in the cover, electrical means in the housing for lighting the lamp, means in the housing between the lamp and the funnel

for directing light from the lamp through the funnel, means for expelling liquid that collects at the tip of the funnel, and conduit means through the housing connecting the means for expelling the fluid and a portion of the seating surface facing into the top of the funnel.

7. An apparatus for centering a spinning funnel in a spinning bucket comprising a housing, a surface for seating said housing on the funnel, a cover secured to said housing, an annular projection extending from the housing having a removable annular adapter fitting therein for seating said housing over the funnel, a lamp in the cover, electrical means in the housing for lighting the lamp, means in the housing between the lamp and the funnel for directing light from the lamp through the funnel, means for expelling liquid that collects at the tip of the funnel, and conduit means through the housing connecting the means for expelling the fluid and a portion of the seating surface facing into the top of the funnel.

8. An apparatus for centering a spinning funnel in a spinning bucket comprising a housing, a surface for seating said housing on the funnel, a cover secured to said housing, an annular projection extending from the housing having a removable annular adapter fitting therein for seating said housing over the funnel, a lamp in the cover, electrical means in the housing for lighting the lamp, a microscopic lamp lens system in the housing between the lamp and the funnel for directing light from the lamp through the funnel, means for expelling liquid that collects at the tip of the funnel, and conduit means through the housing connecting the means for expelling the fluid and a portion of the seating surface facing into the top of the funnel.

9. An apparatus for centering a spinning funnel in a spinning bucket comprising a housing, a surface for seating said housing on the funnel, a cover secured to said housing, an annular projection extending from the housing having a removable annular adapter fitting therein for seat-

ing said housing over the funnel, a lamp in the cover, electrical means in the housing for lighting the lamp, a microscopic lamp lens system in the housing between the lamp and the funnel for directing light from the lamp through the funnel, a pressure bulb for expelling liquid that collects at the tip of the funnel and conduit means through the housing connecting the pressure bulb and a portion of the seating surface facing into the top of the funnel.

10. An apparatus for centering a spinning funnel in a spinning bucket comprising a housing, a cover secured to said housing, an annular projection extending from the housing having a removable annular adapter fitting therein for seating said housing over the funnel, a lamp in the cover, electrical means in the housing for lighting the lamp, a microscopic lamp lens system in the housing between the lamp and the funnel for directing light from the lamp through the funnel, and a pressure bulb for expelling liquid that collects at the tip of the funnel connecting to a passage in the housing that vents to the atmosphere above the funnel.
